REFRIGERATING APPARATUS

George C. Pearce, Dayton, Ohio, assignor, by
mesne assignments, to General Motors Cor-
poration, a corporation of Delaware

Application June 18, 1932, Serial No. 618,007

8 Claims. (Cl. 200—81)

This invention relates to refrigerating apparatus, and more particularly to control mechanisms for use with such apparatus and other general purposes.

5 In the use of a mechanically cooled refrigerator, frost collects on the evaporator or cooling unit due to the fact that the temperature thereof is normally below 32° F. To efficiently operate such apparatus it is necessary to remove this 10 frost occasionally and heretofore this has been accomplished by providing mechanism in conjunction with the apparatus for preventing the operation thereof and thereby permitting the temperature of the cooling unit to rise above 15 32° F. to melt the frost and ice therefrom. Such mechanism has heretofore included means for automatically resetting the refrigerating apparatus to normal operation after completion of the defrosting cycle.

20 Such mechanisms have had the disadvantage that it was impossible to restore the system to normal operation after a defrosting cycle had begun until the completion of the defrosting cycle. This made it inconvenient when there was 25 a particular demand for refrigeration, such as for freezing ice cubes.

It is therefore an object of my invention to provide a control mechanism which may be manually initiated to prevent the operation of a refrigerating system in order to provide for defrosting and which will automatically restore the system to normal operation after a defrosting period or cycle but which may be restored to normal operation any time during the defrosting cycle if it is 35 desired to do so.

It is also customary to provide an overload means for opening an electric circuit, such as the electric motor circuit of a refrigerating system, when a dangerous temperature condition 40 arises, and to provide a manually operable means for resetting the overload means. However, with such an apparatus when the trouble causing the dangerous temperature condition is uncorrected, the electric motor will start and run for a short 45 period of time and then the overload means will again open the circuit. This, if repeated a sufficient number of times, will injure the apparatus sought to be protected by the overload means. An even more destructive possibility is that the 50 operator, not knowing of the consequences, might hold the manually operable means in resetting position so as to prevent the tripping of the overload means regardless of the dangerous temperature condition.

55 It is therefore another object of my invention

to provide a means for holding open the electric circuit which is necessarily operative when the overload means is being reset.

Further objects and advantages of the present invention will be apparent from the following description, reference being had to the accompanying drawings, wherein a preferred form of the present invention is clearly shown.

In the drawings:

Fig. 1 is a view in elevation of my improved 10 control mechanism together with a diagrammatic representation of the remaining elements of a compression refrigerating system;

Fig. 2 is a sectional view along the line 2—2 of Fig. 1;

Fig. 3 is a side view of the control mechanism shown in Fig. 1;

Fig. 4 is a sectional view taken along the line 4—4 of Figs. 2 and 3, and

Fig. 5 is a top view of the control mechanism, 20 the indicating plate attached.

Referring to the drawings and more particularly to Fig. 1 there is shown for the purpose of illustrating my invention a refrigerating system comprising a compressor 20 for compressing the 25 refrigerant and for forwarding the compressed refrigerant to the condenser 21 where the refrigerant is liquefied and collected in the receiver 22. From the receiver 22 the liquid refrigerant is forwarded through a supply conduit 23 through 30 the expansion valve 24 or cooling unit 25. In the evaporator the liquid refrigerant vaporizes under a reduced pressure and the resulting vapors are returned to the compressor through the return conduit 26. The compressor 20 is driven 35 by an electric motor 27 through a suitable pulley and belt means 28.

In order to control the temperature of the evaporator 25 I provide a thermostatically controlled switch means generally designated by the 40 reference character 30 which is connected in series with the electric motor circuit 29 for controlling the operation of the electric motor and compressor.

This switch means has a housing 31 formed of 45 insulating material, such as hard rubber or a phenol condensation product, to which is attached a generally C-shaped sheet metal framework 32, the bottom portion 33 of which is forked to receive the lower end of a siphon bellows 34 50 which is clamped to the forked bottom portion 33 by a nut 35. The interior of the bellows 34 is connected by means of a conduit 36 to a thermostatic bulb 37 which is located near the evaporator 25. The C-shaped member is connected to 55

the insulated member 31 by a pair of ears 106 and 107. The C-shaped member 32 has a projecting portion 38 provided with a pair of knife edges 39 which pivotally support one end of the bellows follower or main lever 40. The bellows follower 40 consists of an irregularly shaped plate member having notches 41 which receive projections 42 of the projecting portion 38 to hold the bellows follower 40 from lateral displacement. 5 The bellows follower 40 has a turned down projection 43 which rests upon the top plate 44 of the bellows 34. The top plate 44 is guided in its vertical movement by a pair of vertical pins 45 which are fixed to the bottom plate 46 of the 10 bellows 34. The bellows follower 40 has an upturned projection 47 upon which rests a spring retainer 48 which supports the bottom of the main adjustment spring 49. At the top of the main adjusting spring 49 is an upper spring retainer which is threaded upon the main adjusting screw 51. The upper spring retainer 50 has a lug 52 at one side which rides within a vertical groove 53 in the insulated housing 31. At the 15 top of the main adjusting screw 51 there is provided a cold control knob 54 to provide a customer's adjustment to vary the average temperature of the evaporator.

At one side of the bellows follower 40 is a T-shaped lug 55 which projects through a slot or aperture 56 in a differential plate 57. The differential plate 57 is provided with an upper aperture 58 through which projects a pin 59' which is fixed to a C-shaped metal member 32. At the upper end of the differential plate 57 there is 20 connected a differential spring 59 which is suspended from a differential adjustment member 60 threaded upon a differential adjusting screw 61. The differential adjustment member 60 has a depending portion 62 which bears against the wall of the insulated housing member 31 to prevent its rotation. The differential adjustment spring 59 is held under tension at all times by a differential adjustment member 60 so as to hold the differential plate 57 in its upper position in 25 which the pin 59' engages the lower edge of the aperture 58 to prevent further upward movement.

Upon the projecting portion 64 of the bellows follower 40 there is provided member 65 of insulating material which extends through an aperture 66 in the side wall 67 of the insulated housing 31. This insulated member 65 has a forked end provided by the notch 68 and the prongs 69 and 70 which have V-shaped recesses 71 and 72 respectively formed on their inner sides which receive the knife edges 73 formed upon the ends of the U-shaped sheet metal secondary lever 74. The U-shaped sheet metal secondary lever 74 is held against the knife edges by the toggle spring 75 which has one end connected to a T-shaped member 76 which passes through an aperture in the metal portion of the secondary lever 74. The open end of the toggle spring 75 is connected to an upstanding ear 77 which projects between the prongs 69 and 70 of the insulating member 65.

This ear 77 forms a part of an irregularly shaped switch contact member generally designated by the reference character 78. This member 78 has a pair of rearwardly turned ears 79 and 80 pivotally mounted upon the pivot pin 81 which has its end fixed in a rear wall 82 of the insulated housing 31. The irregularly shaped member 78 has one arm 83 extending horizontally which terminates in the above mentioned upstanding ear 77. One portion 84 of the arm

83 is bent up so as to provide a stop for the free end of the secondary lever 74. The irregular shaped member 78 has a lip 85 projecting so as to form another stop member for the free end of the secondary lever 74 to limit its upper movement. Another arm 87 extends downwardly and has a switch contact bar 88 riveted to its lower end. The lower end of this arm 87 has a pair of projections 89 formed thereon which rest against the contact bar 88 forming guides to hold it in place and prevent rotation upon the single rivet 90. The switch contact bar 88, when in closed position, bridges the contacts 91 and 92 which are fixed to the bottom wall 93 of the housing 31. The irregularly shaped member 78 also has another arm 94 extending upwardly which has a bent portion at its upper end for a purpose hereinafter to be described.

The operation of this portion of the apparatus will now be described. As the temperature of the evaporator increases, the volatile liquid in the thermostat bulb 37 vaporizes and causes an increase in pressure within the bellows 34. This increase in pressure within the bellows 34 exerts a force upon the bellows follower 40 against the tension of the main adjusting spring 49. This pressure gradually moves the bellows follower upwardly against the tension of the main adjusting spring 49 thereby causing the double toggle mechanism to be tripped. The double toggle mechanism is tripped by the moving of the pivot point of the secondary lever by the bellows follower above the center line of the toggle spring thereby causing the secondary lever 74 to move quickly from its extreme upper position to the extreme lower position thereby rotating the irregularly shaped contact member 78 counterclockwise to bridge the main switch contacts 91 and 92. The bridging of the main switch contacts 91 and 92 permits electric energy to flow through the electric circuit to the driving motor 27 to operate the compressor which will then lower the temperature of the evaporator 25. The lowering of the pressure in the evaporator 25 will reduce the pressure within the thermostat bulb 37 and the bellows 34 causing a retraction of the bellows follower 40 under the pressure of the main adjusting spring 49. As the bellows follower 40 moves downwardly in a clockwise direction about the knife edges 39 a predetermined distance, the T-shaped boss 55 upon the bellows follower 40 will strike the bottom of the differential plate 57 causing the differential plate 57 to move downwardly along with the bellows follower against the tension of the differential spring 59. This will provide the additional resistance of the adjustable tension of the differential spring to the downward movement of the bellows follower 40 and in this way, a differential adjustment is provided for varying the pressure at which the main spring contacts 91 and 92 will be opened and closed.

In order to defrost the evaporator, I provide a manual control member 101 which has its upper portion projecting through the top wall 65 102 of the insulated member 31 and which has its lower portion of a semi-circular shape pivotally mounted upon a pin 103 which is supported by an insulated boss 104. The boss 104 is fastened to the top wall 102 of the insulated member 31 by a screw 105. At one corner of the semi-circular portion of a manual control member 101 there is provided a pin 108 which is fastened therein. A toggle spring 109 has one end con-

nected to the pin 108 and has its opposite end connected by means of a pin 110 to the side wall 111 of the insulated housing 31. This toggle spring normally holds the manual control member 101 in ineffective or "run" position. Extending downwardly from the pin 108 is a link 112 which has a lost motion slot 113 at its lower end. The lost motion slot 113 is connected by means of a pin 114 to the insulated member 65 which forms 5 a part of the bellows follower 40.

When the manual control member 101 is in the position shown in Fig. 1, namely the "run" or ineffective position, the defrosting mechanism is ineffective and the pin 114 moves freely with- 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

ity to the electric heater 116 is a bi-metallic strip 118 which has one end fastened within a pivot block member 119 of insulating material which is pivotally mounted upon a pin 120 fixed to the insulated housing 31. A second bi-metallic strip 5 121 has its one end fixed within the insulated pivot member 119. This second strip extends outwardly from the pivot block member at an angle of approximately 60° to the bi-metal strip 118. The outer end of the bi-metal strip 121 is held 10 against an adjusting pin 122 which has a threaded upper end 123 which is threadedly mounted within the side wall 111 of the insulated member 31. The upper end of the adjusting pin 122 is provided with a slot for a screw driver to adjust 15 the position of the bi-metal strip 118. In order to hold the outer end of the bi-metal strip 121 against the end of the adjusting end 122, there is provided a movable pin 124. The pin 124 has one end slidably mounted within the boss 125 20 which projects from the rear wall 82 of the insulated member 31. At the opposite end of the pin 124, there is a collar 126 which is held in place by the snap ring 127. Between the collar 126 and the box 125 there is a compression spring 128 25 which presses against the collar 126 for holding the pin 124 in engagement with the outer end of the bi-metal strip 121.

The bi-metal strip 118 and the bi-metal strip 121 are both affected by room temperature to the same degree. The bi-metal strip 121 is provided for compensating the bi-metal strip 118 from changes in room temperature. The bi-metal strip 121 compensates the bi-metal strip 118 by 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

The outer end of the bi-metal strip 118 has a shoulder portion 130 of an overload contact member 131 resting against it. The overload contact member is provided with a pair of ears 132 which are pivotally mounted upon a pin 133 which is fixed to the rear wall 82 of the insulated housing 31. The overload contact member 131 is held in yielding engagement with the end of the bi-metal strip 118 by the overload spring 134 which has one end connected to a pin 135 fixed to the rear wall 82 of the insulated housing member 31 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

It should be understood that the temperature of the evaporator 25 must rise to a temperature of from 40 to 50° F. in order to provide sufficient pressure within the thermostatic bellows 34 to return the manual control member 101 to normal running position to terminate the defrosting cycle. It will thus be seen that the defrosting mechanism is at all times under the control of the housewife and may be initiated or terminated at will; but even if the defrosting cycle is initiated by the housewife, the frosting mechanism will be returned to ineffective position after a predetermined pressure is exerted within the interior of the bellows 34.

In order to properly protect the electric motor, I provide an improved thermal overload mechanism. After the electric current passes 70 from the contact 91 across the contact bar 88 to the contact 92, it passes through an electric heater 116 formed of a serpentine-shaped section of nickel chromium wire which is connected at one end to the switch contact 92 and at the other 75 end to the overload contact 117. In close proxim-

overload contact bar 137 from the overload contacts 117 and 142 to open the electric motor circuit 29. In this connection the spring mounting of the overload contact bar 137 will cause an 5 abrupt removal of the contact bar from the overload contacts, thereby preventing excessive arcing.

A manual reset member 150 which has one portion projecting through the top wall 102 of the 10 insulating member 31 and which has its lower semi-circular portion mounted upon the pin 103, is provided for re-setting the over-load contacts to closed circuit position. The manual re-set member 150 normally is resiliently held in "on" 15 position by a tension spring 151. Upon the tripping of the overload contact member 131, the upper end 152 thereof will engage the one end 153 of the manually re-set member 150 and move the re-set member to "off" position. In re-setting 20 the overload contact member, the manual reset member 150 is moved to resetting position against the tension of the spring 151, thereby causing the shoulder 153 to engage the end portion 152 of the overload contact member 131. 25 This will rotate the contact member 131 in a clockwise direction to cause the contact bar 137 to engage the overload contacts 117 and 142 which will close the electric circuit 29 and permit the bi-metal strip 118 to again move into engagement 30 with the shoulder portion 130 of the overload contact member 131.

At the same time, the lug 154 will engage the upper arm 94 of the main switch contact member to move the main contact bar to open circuit position during the time the overload contact bar 137 is closing the overload switch contact. This will prevent the arcing of the overload contact when returning them to closed circuit position and in addition will prevent the 40 starting of the electric motor until the overload mechanism is reset and held in closed circuit position by the bi-metal strip 118. If the bi-metal strip is too warm, the electric motor circuit 29 can therefore not be closed. This also prevents 45 the housewife from forcibly holding the electric circuit closed and forcing the electric motor to run under a dangerous condition which might materially injure or destroy the electric motor.

The overload mechanism is also used as a 50 means for shutting down the refrigerating system. When the manual reset member 150 is moved to "off" position the lug 154 engages the compensating bi-metal strip 121 to move the bi-metal strip 118 counter-clockwise to disengage 55 the outer end of the bi-metal strip 118 from the shoulder portion 130 of the overload contact member 131 to permit the contact member 131 to move to open circuit position. The overload contact member 131 will then remain in open circuit 60 position to prevent operation of the electric motor and the refrigerating system until the overload mechanism is reset.

While the form of embodiment of the invention as herein disclosed, constitutes a preferred form, 65 it is to be understood that other forms might be adopted, all coming within the scope of the claims which follow.

What is claimed is as follows:

1. A circuit controlling apparatus including 70 pressure responsive means for opening and closing an electric circuit for providing open and closed cycles according to certain pressures, a manually controllable means having an effective and an ineffective position, said manually controllable means being movable at will from effec-

tive to ineffective position and from ineffective to effective position, and means operatively connecting said pressure responsive means and the manually controllable means when in effective position for applying an additional force upon the pressure responsive means to provide a prolonged cycle, said manually controllable means being movable to ineffective position during a prolonged cycle to terminate prematurely a prolonged cycle, said connecting means being also 10 operated by said pressure responsive means to return said controllable means from effective to ineffective position.

2. A circuit controlling apparatus including 15 pressure responsive means for opening and closing an electric circuit responsive to pressures to provide open and closed circuit cycles, a manual control member and snap acting means including spring means for resiliently urging the manual control member into either of two positions, a 20 dial cooperating with said manual control member for indicating an effective and an ineffective position, the manual control member being movable at will from effective position to ineffective position, said manual control member when in effective position only being effective to cause 25 said spring means to exert a force upon said pressure responsive means for providing a prolonged cycle, said manual control member being movable at will during the prolonged cycle from the effective position to the ineffective position to move the spring means to ineffective position and to remove said force upon the pressure responsive means to terminate at will the prolonged cycle, said pressure responsive means being effective 30 during the prolonged cycle to move the manual control member to ineffective position automatically to return the apparatus to normal operation.

3. A circuit controlling apparatus including 35 a pressure responsive means for opening and closing a set of contacts in an electric circuit, a set of overload contacts in said electric circuit in series with said pressure operated contacts, yielding means for moving said overload contacts to open position, a temperature responsive latch 40 means for preventing the yielding means from moving said overload contacts to open position, said latch means being tripped at a predetermined temperature to permit the overload contacts to be opened by said yielding means, a 45 manual control member for opening and closing the overload contacts and for resetting the overload contacts to closed position, and means actuated by said manual control member when resetting the overload contacts to closed position 50 for holding open said pressure operated contacts.

4. A refrigerator switch including pressure responsive means for opening and closing an electric circuit according to certain pressures, a snap 55 acting means including a manual control member movable to effective and ineffective positions, said snap acting means and said manual control means being movable into and out of the effective and ineffective positions as a unit, said snap acting means when moved to effective position having means movable into the path of the pressure responsive means to act upon the pressure responsive means to change the pressure at which the pressure responsive means operates, said 60 pressure responsive means being operative upon a predetermined change in pressure to move the snap acting means out of its path of movement.

5. A switch including pressure responsive means for opening and closing an electric circuit, a finger manipulative device, a snap acting device 65

cooperating with said manipulative device for resiliently holding said manipulative device in any one of a plurality of positions, one of said devices having means for engaging the pressure responsive means when the finger manipulative device is in one of its positions to resist the movement of the pressure responsive means, said pressure responsive means being effective to move the finger manipulative device from one position to another.

6. A control including pressure responsive means for controlling a means to be operated, a finger manipulative toggle device having an operative and inoperative position, said device including means effective when in operative position for controlling the movement of the pressure responsive means, said pressure responsive means being effective to move said device from one position to another, said finger manipulative toggle device being freely movable at will as a unit to and from the operative position to control or remove its control from the pressure responsive means whenever desired.

7. A circuit controlling apparatus including a set of switch contacts in an electric circuit, pressure responsive means for opening and closing

said contacts, a set of overload switch contacts in said electric circuit in series with said pressure operated contacts, temperature responsive means for opening the overload contacts, a manual control member for resetting the overload contacts to closed position, and means actuated by force derived from the manual control member when resetting the overload contacts to closed position for holding open said pressure operated contacts.

8. A circuit controlling apparatus including a set of switch contacts in an electric circuit, pressure responsive means for opening and closing said contacts, a set of overload switch contacts in said electric circuit in series with said pressure operated contacts, means responsive to an excessive flow of current through said electric circuit for opening the overload contacts, means responsive to the environment temperature for compensating said current responsive means, a manual control member for resetting the overload contacts to closed position, and means actuated by force derived from the manual control member when resetting the overload contacts to closed position for holding open said pressure operated contacts.

GEORGE C. PEARCE.
